UNITED STATES PATENT OFFICE.

MAX SCHÄFER, OF STUTTGART, GERMANY, ASSIGNOR TO THE FIRM ROBERT BOSCH AKTIENGESELLSCHAFT, OF STUTTGART, GERMANY.

DEVICE FOR SIMULTANEOUSLY STARTING A PLURALITY OF INTERNAL-COMBUSTION ENGINES.

1,424,185.

Specification of Letters Patent. Patented Aug. 1, 1922.

Application filed December 12, 1919. Serial No. 344,477.

To all whom it may concern:

Be it known that I, MAX SCHÄFER, a citizen of Germany, residing at Stuttgart, Germany, have invented certain new and useful 5 Improvements in Devices for Simultaneously Starting a Plurality of Internal-Combustion Engines, (for which I have filed an application in Germany September 2, 1918, No. 319,065), of which the following 10 is a specification.

Many internal combustion engines for aeroplanes and airships are now made with a very large number of cylinders. The usual 15 numbers of cylinders in earlier practice were six and eight, but now-a-days twelve cylinders are frequently met with. If the speed of engines having a high number of cylinders, say twelve, exceeds a certain limit, it is not impossible that the magneto ignition 20 apparatus arranged for the ignition of all of the twelve cylinders will fail, because the interruptions of the primary circuit occur in a too rapid succession. High speed twelve cylinder engines of this kind are therefore 25 frequently ignited in two groups with two six-cylinder ignition apparatus in such a manner as to cause each ignition brought about by one apparatus to be followed when the engine crank has turned through an angle of 60°, by an ignition due to the other 30 apparatus.

In the same measure as the described substitution of a twelve-cylinder ignition apparatus by two six-cylinder ignition apparatus is suitable for causing ignitions during the regular working of the engine, it is 35 unsuitable for this purpose in the case of starting ignition devices having starting magnetos with crank handles. For if the 40 starting magneto were to be connected to only one of the two six-cylinder apparatus, only one group of six cylinders of the twelve-cylinder engine would be supplied with ignition currents. The starting ignitions of 45 two consecutive cylinders would then occur at intervals corresponding to crank turns of 120°, instead of 60° as required. But intervals of 120° are too large because with such intervals a single starting ignition 50 would have to overcome the resistance of compression of several cylinders.

If recourse were had to another expedient, which consists in dividing the current lead from the one starting magneto used into two

branches, and in connecting each branch to 55 one of the six-cylinder apparatus equipped with a starting device, there would be a possibility that, when the rotating distributing member is in certain positions, the starting igniting currents would not ignite the cylinders in the proper order in which they are 60 ignited during the normal running of the engine, when an ignition occurs at every 60° of rotation of the crank shaft, but that the current would leave out the 65 correct cylinder in the sequence and pass on to the next cylinder on account of the spark gap of the correct cylinder happening to be in a less favorable condition for the passage of an ignition current than 70 the said next cylinder. For this reason the connecting of one and the same starting magneto to two six-cylinder apparatus can- 75 not be recommended.

The same difficulties are encountered if, instead of equipping an aeroplane with a twelve cylinder engine, two separate six-cylinder engines are employed, and at each ignition one cylinder of the one engine is ignited together with a cylinder of the other engine. 80

The drawbacks described above will be immediately removed if a separate starting magneto is connected to each six-cylinder apparatus and both starting magnetos are driven together, for example by a common 85 coupling member such as a driving chain or the like. But this expedient would be cumbersome and expensive.

The object of this invention is to obviate this cumbersomeness and expense by enabling the sub-divided cylinder groups of an engine with a high number of cylinders, or a plurality of separate engines, to be started in a reliable manner by a single magneto. 90

This object is accomplished by a device in which each engine, or each cylinder group of an engine with a high number of cylinders, has a main ignition apparatus that operates during the ordinary running of the 100 engine and that is equipped with a starting ignition device, and in which a single starting magneto is connected to the various main ignition apparatus through the medium of a distributor in such manner that the current 105 impulses produced in the starting magneto are alternately conducted to the various main ignition apparatus. The distributor

is most simply arranged in the immediate neighbourhood of the starting magneto, the end of the secondary winding of this magneto terminating in a rotating distributing member which moves past a set of fixed distributor segments or sparking points which are equal in number to the number of main ignition apparatus. If two main apparatus are to be supplied with starting current the 10 rotating distributing member is mounted upon the shaft of the magneto armature and co-operates with two fixed distributor contacts which are displaced on a circle by 180°. But if more than two main apparatus or 15 magnetos are used the distributor contacts and the rotating distributor member is geared in such manner that whenever the armature of the starting magneto generator has executed a turn of 180° a current impulse 20 will pass into a fixed distributor contact.

Since an ignition by starting ignition sparks shall still be possible at speeds of the internal combustion engine amounting to 200 to 300 revolutions per second, the 25 number of current impulses produced by the ordinary magneto generators will not suffice in the case of a large number of engines or of engines with a number of cylinders as high as twelve. This difficulty is met by 30 a further feature of the invention which consists, either in driving the armature of the starting magneto by gear-wheels inserted between the crank-handle and the armature at a specially high speed, or in 35 employing flux-directing members that rotate between a fixed armature and the magnet pole faces of the magneto generator so as to affect the paths taken by the magnetic lines of force that pass from the pole faces 40 and through the iron core of the stationary armature.

If, for example, a cylindrical iron shell with two windows or perforations is used as a flux-directing member, four current impulses will be obtained at each revolution of the shell and it will therefore be possible to mount the rotating distributor member upon the armature shaft, and to arrange around this member four stationary distributor contacts or current-receiving members at angular intervals of 90°.

A manner of carrying out the invention is diagrammatically illustrated in the drawing in which a twelve cylinder engine is represented with its cylinders divided into two groups. For convenience of illustration the one group of six cylinders is shown above the other group. The upper group is associated with the normal or main ignition apparatus A and the lower group of cylinders is associated with the main ignition apparatus B. These main ignition apparatus, of which the distributors only are shown, comprise starting ignition devices which are in 65 themselves known (see German Patent No.

253894). (An auxiliary brush for distributing starting ignition currents, which in standard machines is made in a shape of a nickel point from which sparks jump to the stationary distributor members, is arranged 70 to lag behind the brush that distributes ignition current during the normal running of the engine. Hence the starting ignition current is always only able to pass through a normal ignition apparatus into the particular explosion cylinder whose piston has just passed its dead point position).

In the drawing the secondary winding D, and the distributor E, which is a feature of the invention, represent the starting magneto generator C which is arranged to be driven by a crank handle (not shown). The end of the secondary winding D which is not connected to earth leads to the metallic sparking member f that rotates with the 80 armature shaft of the starting magneto. Fixed in a stationary distributor disk composed of insulating substance are the sparking points g and h. The distributor point g is connected to the lagging point i of the 85 normal or main ignition apparatus A, and the distributing point h is connected to the lagging point k of the main ignition apparatus B.

The device operates in the following 90 manner: At every half of a revolution executed by the starting magneto generator C when turned by its crank handle, a current impulse is produced, and these impulses are distributed through the sparking points g 100 and h to the ignition apparatus A and B alternately. By thus compelling the starting ignition currents to be distributed to the two main ignition apparatus in the described manner, a starting ignition is produced in the engine at every 60° of revolution of the crank, because the gearing of the two main ignition apparatus or distributors is such that each ignition current sent through one distributor into the engine is 110 followed, after the engine crank has turned through another 60°, by an ignition current through the other main distributor. In other words, the intervals between the ignition currents sent through any one of the main distributors, amounting to 120° of rotation of the engine crank, are divided by starting ignition currents sent at the middle 115 of each interval through the second main distributor.

If an aircraft or land vehicle is equipped with two six-cylinder engines that are to be started at the same moment, the distributor of the starting magneto is arranged in the same way, and the two normal or main distributors are connected as illustrated. If the vehicle has three separate engines or a multi-cylinder engine whose cylinders are arranged in three groups with separate ignition apparatus, the distributor disk of the 120 125 130

- starting magneto is arranged so that the rotating sparking member f is driven at $\frac{1}{3}$ of the speed of the armature. The rotating member f will then move past three stationary sparking points which are disposed around the circle at intervals of 120° . In the case of four separately ignited cylinder groups of a multi-cylinder engine the rotating distributing member f is driven at one-half of the speed of the starting magneto armature and four stationary distributor points 90° apart are connected to the lagging current-transferring or sparking points of the four normal distributor. 15 It may happen that the cylinder groups of an engine are still to receive starting ignition current when the speed attained during the operation of starting has reached 200 to 300 revolutions. In order to produce 20 the large number of current impulses in the starting magneto that would then be required per minute, the armature of the same would have to be driven at an extraordinary high speed, especially if more than two cylinder groups are to be dealt with. This can be accomplished by a step-up gearing arranged between the crank handle and the armature. A preferred method of producing 25 a high number of impulse consists in making the armature stationary, and arranging a rotating, slotted, iron, flux-affecting shell between the pole faces and the armature of the starting magneto. With four cylinder groups for instance the cylindrical flux-affecting shell would have two slots and the 30 current-transferring member f would be arranged to rotate with it. This member would then receive four current impulses in each revolution of the shell. 35 The scope of the invention is not limited to systems shown in the German Patent No. 253894, but also includes other systems if 40
- applied in the sense of the above description.
- I claim:
- Groups of cylinders of an internal combustion engine or engines, each group having a separate normal ignition apparatus with a normal ignition current distributor, in combination with a starting ignition device comprising a starting current distributing member in each normal distributor, a single starting magneto generator for generating starting currents, and an auxiliary distributor for alternately transferring current impulses produced by the starting magneto generator to the said various distributing members in the normal distributor. 45
  - Groups of cylinders of an internal combustion engine or engines, each group having a separate normal ignition apparatus with a normal ignition current distributor, in combination with a starting ignition device comprising a starting current distributing member in each normal distributor, a single starting magneto generator for generating starting currents, and an auxiliary distributor for alternately transferring current impulses produced by the starting magneto generator to the said various distributing members in the normal distributor. 50
  - Groups of cylinders of an internal combustion engine or engines, each group having a separate normal ignition apparatus with a normal ignition current distributor, in combination with a starting ignition device comprising a starting current distributing member in each normal distributor, a single starting magneto generator for generating starting currents, and an auxiliary distributor for alternately transferring current impulses produced by the starting magneto generator to the said various distributing members in the normal distributor. 55
  - Groups of cylinders of an internal combustion engine or engines, each group having a separate normal ignition apparatus with a normal ignition current distributor, in combination with a starting ignition device comprising a starting current distributing member in each normal distributor, a single starting magneto generator for generating starting currents, and an auxiliary distributor for alternately transferring current impulses produced by the starting magneto generator to the said various distributing members in the normal distributor. 60
  - Groups of cylinders of an internal combustion engine or engines, each group having a separate normal ignition apparatus with a normal ignition current distributor, in combination with a starting ignition device comprising a starting current distributing member in each normal distributor, a single starting magneto generator for generating starting currents, and an auxiliary distributor for alternately transferring current impulses produced by the starting magneto generator to the said various distributing members in the normal distributor. 65
  - Groups of cylinders of an internal combustion engine or engines, each group having a separate normal ignition apparatus with a normal ignition current distributor, in combination with a starting ignition device comprising a starting current distributing member in each normal distributor, a single starting magneto generator for generating starting currents, and an auxiliary distributor for alternately transferring current impulses produced by the starting magneto generator to the said various distributing members in the normal distributor. 70
  - Groups of cylinders of an internal combustion engine or engines, each group having a separate normal ignition apparatus with a normal ignition current distributor, in combination with a starting ignition device comprising a starting current distributing member in each normal distributor, a single starting magneto generator for generating starting currents, and an auxiliary distributor for alternately transferring current impulses produced by the starting magneto generator to the said various distributing members in the normal distributor. 75

In testimony whereof I have affixed my signature in presence of two witnesses.

MAX SCHÄFER.
